(57) **CLAIM**

I claim the ornamental design for a container with integral retractable pouring spout, as shown and described.

DESCRIPTION

FIG. 1 is a front top left perspective view of a container with integral retractable pouring spout showing my new design in a closed position;

FIG. 2 is a rear bottom right perspective view thereof;

FIG. 3 is a front view thereof;

FIG. 4 is a right view thereof, the left view being a mirror image;

FIG. 5 is a rear view thereof;

FIG. 6 is a top view thereof;

FIG. 7 is a bottom view thereof;

FIG. 8 is a front top left perspective view the container with integral retractable pouring spout shown in an open position;

FIG. 9 is a rear bottom right perspective view thereof;

FIG. 10 is a front view thereof;

FIG. 11 is a right view thereof, the left view being a mirror image;

FIG. 12 is a rear view thereof;

FIG. 13 is a top view thereof;

FIG. 14 is a bottom view thereof; and,

FIG. 15 is a top view thereof shown in an unfolded blank configuration.

The broken lines shown represent portions of the container with integral retractable pouring spout that form no part of the claimed design.

The short dash-long dash broken lines shown represent fold lines and form part of the claimed design.

1 Claim, 7 Drawing Sheets
